(21) Appl. No.: **29/167,045**

(57) **CLAIM**

(22) Filed: **Sep. 5, 2002**

The ornamental design for a shunt receptacle and plug
device, as shown and described.

(51) **LOC (7) Cl. 13-03**

DESCRIPTION

(52) **U.S. Cl. D13/146**

FIG. 1 is a perspective view of a shunt receptacle and plug
device showing my new design;

(58) **Field of Search** D13/133, 146,
D13/147, 156; 439/136, 138, 142, 638,
188, 507, 510

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective exploded view of a shunt receptacle
and plug device showing my new design.
